Primary Examiner—Caron D. Veynar*Assistant Examiner*—Garth Rademaker(74) *Attorney, Agent, or Firm*—Park & Associates, PC(57) **CLAIM**

The ornamental design for photograph holding pot planter, as shown and described.

DESCRIPTION

FIG. 1 is a perspective view of a photograph holding pot planter showing my new design.

FIG. 2 is a front elevation view thereof.

FIG. 3 is a left side elevation view thereof.

FIG. 4 is a right side elevation view thereof.

FIG. 5 is a rear elevation view thereof.

FIG. 6 is a top plan view thereof; and,

FIG. 7 is a bottom plan view thereof.

The broken line showing in FIG. 2 is for illustrative purposes only and forms no part of the claimed design.
